(57) CLAIM

The ornamental design for footwear, as shown and described.

DESCRIPTION

FIG. 1 is a front perspective view of a shoe showing my footwear design;

FIG. 2 is a left side view of the footwear shown in FIG. 1;
FIG. 3 is a right side view of the footwear shown in FIG. 1;
FIG. 4 is a front view of the footwear shown in FIG. 1;
FIG. 5 is a rear view of the footwear shown in FIG. 1; and,
FIG. 6 is a top view of the footwear shown in FIG. 1.

The broken line showing of the sole, heel, zipper, footbed, rivets and heel cap in the relevant drawings shows unclaimed subject matter for the design in those drawings.

The break lines shown in the drawings of the laces indicate unclaimed length.
